ELECTRIC MASSAGER

Kurt F. Mizen, Evanston, Ill., assignor to Burges Vibro-crafters, Inc., Grayslake, Ill., a corporation of Delaware

Filed Mar. 8, 1968, Ser. No. 10,900

Term of patent 14 years

(Cl. D83—1)

FIG. 1 is a top perspective view of an electric massager showing my new design;

FIG. 2 is a side elevation view thereof taken from the right side of FIG. 1;

FIG. 3 is a top plan view thereof, and

FIG. 4 is a bottom plan view thereof on a somewhat reduced scale.

The essential features of the design reside in the portions shown in solid lines in the drawings.

I claim:

The ornamental design for an electric massager, substantially as shown and described.
